UNITED STATES PATENT OFFICE.

OTTO J. ORSER, OF GORDON, ONTARIO, CANADA.

SIGNALING DEVICE FOR TRADESMEN.

1,135,915.

Specification of Letters Patent. Patented Apr. 13, 1915.

Application filed November 8, 1913. Serial No. 800,005.

To all whom it may concern:

Be it known that I, Otto J. ORSER, a citizen of the United States, residing at Gordon, in the Province of Ontario and Dominion of Canada, have invented new and useful Improvements in Signaling Devices for Tradesmen, of which the following is a specification.

This invention relates to improvements in signaling devices and has particular application to a tradesman's signal.

In carrying out the present invention, it is my purpose to provide a device of the class described which may be secured to the exterior of a residence and whereby passing tradesmen may be notified that the occupants of the dwelling wish to purchase their wares.

It is also my purpose to provide a device of the class described which will embody among other features a casing having an open front wall adapted to be closed by means of a door and signal plates within the casing and removable therefrom and having indicia thereon indicative of the tradesmen wanted and adapted to be removed from the casing, when the occupant of the dwelling desires to attract a tradesman's attention, and hung upon the exterior of the casing.

Furthermore, I aim to provide a signaling device for tradesmen which will embrace the desired features of simplicity, efficiency and durability and which may be manufactured, marketed and installed at a minimum expense.

With the above and other objects in view, the invention consists in the construction, combination and arrangement of parts hereinafter set forth in and falling within the scope of the claim.

In the accompanying drawings; Figure 1 is a view in front elevation of a signaling device constructed in accordance with my present invention, the same being shown as fixed to the exterior of a dwelling and having a signal displayed. Fig. 2 is a front elevation of the device removed from the dwelling, the cover being in open position. Fig. 3 is a fragmentary longitudinal sectional view through the casing. Fig. 4 is a transverse sectional view therethrough. Fig. 5 is a cross sectional view through one of the signal plates showing the same on an enlarged scale. Fig. 6 is a view of the signal plate in display position.

Referring now to the accompanying drawings in detail, the numeral 1 designates a casing composed of any suitable material and preferably of rectangular contour in horizontal section. This casing is designed to be fastened to the exterior of a dwelling house or the like in some suitable manner, as, for instance, by screws passing through the rear wall of the casing and entering the material of the support. The front wall of the casing is open and is adapted to be closed by means of a door 2 adapted for swinging movement to open and closed positions and having the lower edge thereof hingedly connected to the forward edge of the bottom wall of the casing as at 3.

Appropriately fastened to the inner surfaces of the opposite end walls of the casing 1 are supporting blocks 4 having the confronting faces thereof formed with horizontal slots 5 spaced apart vertically, the slots in one block alining with those in the other block. Slidably mounted within each pair of alining slots 5 is a signal plate 6 composed of metal or any other suitable material and having the forward edge thereof provided with a flange 7. These signal plates, when within the casing, are disposed in horizontal planes and spaced apart in parallelism, while the flanges 7 on the forward edges thereof depend from the respective plates and are disposed in a vertical plane. When in display position the longitudinal edge of the flange 7 contacts with the door 2 thereby throwing the center of gravity of the signal plates out of a vertical line with the result that the plates are prevented from rattling.

Secured to the top longitudinal edge of the door 2 are hooks 8, 8 appropriately spaced apart, while formed in each signal plate adjacent to the rear edge thereof are apertures 9, 9 spaced apart a distance equal to the distance between the hooks 8, 8 and adapted to receive such hooks when the signal plate is withdrawn from the casing for display purposes. The exposed surface of each signal plate is provided with suitable indicia 10 indicative of the particular tradesman to be signaled by such plate, while the depending flanges of the plates are provided with indicia 11 corresponding with the indicating matter 10 so that when the plates are within the casing, the party employing the device, will know, at a glance, which

plate to select. A suitable spring catch 12 is employed to maintain the cover or door 2 in closed position.

From the foregoing description taken in connection with the accompanying drawings, the construction, mode of operation and manner of employing my invention will be readily apparent. Assuming the casing to be fast to the exterior of a building and the occupant of such building desires to signal a passing tradesman, such occupant releases the spring catch 12 and swings the door 2 to open position. After the door has been opened the signal plate indicative of the tradesman wanted is selected and withdrawn from the casing. The door is now swung to closed position and latched and the signal plate suspended by the hooks 8, 8 and the apertures or eyes 9, 9 formed in the signal plate adjacent to the rear edge thereof. The passing tradesman, upon seeing the signal displayed will act accordingly.

In order that the signal plates may be con-

veniently removed from the casing the depending flange on each plate is equipped with a handle 13 whereby the plates may be readily withdrawn from the slots holding the same.

I claim:

In combination with a casing having interior and exterior supporting means, of signal plates adapted to be supported by said means, each of said plates being provided with a body portion having indicia thereon and a right angularly disposed flange having indicia thereon agreeing with the indicia on the body portion, said flange adapted to throw the center of gravity of the plate to one side of a vertical line when in display position.

In testimony whereof I affix my signature in presence of two witnesses.

OTTO J. ORSER.
